DESIGN FOR A WATCH

Roy Sheldon, New York, N. Y.

Application October 30, 1933. Serial No. 49,602

Term of patent 7 years

To all whom it may concern:

Be it known that I, Roy SHELDON, a citizen of the United States, residing in the city of New York, in the county of New York and State of New York, have invented a new, original, and ornamental Design for a Watch, of which the following is a specification, reference being had to the accompanying drawing, forming a part thereof.

In the drawing:

I claim:

The ornamental design for a watch, as shown and described.

ROY SHELDON.
